United States Patent Office

Des. 196,527
Patented Oct. 8, 1963

196,527

ICE CREAM SCOOP OR SIMILAR ARTICLE

Walter Schlessel, Lawrence, N.Y., assignor to Gessler
Products Corporation, Jamaica, N.Y., a corporation of
New York

Filed May 3, 1963, Ser. No. 74,741

Term of patent 14 years

(Cl. D44—29)

Fig. 1.

Fig. 2.

Fig. 3.

Fig. 4.

Fig. 5.

Fig. 6.

FIG. 1 is a front elevational view of an ice cream scoop or similar article showing my new design;

FIG. 2 is a right side elevational view;

FIG. 3 is a top plan view;

FIG. 4 is a rear elevational view;

FIG. 5 is a left side elevational view; and

FIG. 6 is a bottom plan view thereof.

I claim:

The ornamental design for an ice cream scoop or similar article, as shown.
